UNITED STATES PATENT OFFICE.

HIRAM W. BLAISDELL, OF LOS ANGELES, CALIFORNIA.

TRANSFER MECHANISM.

No. 845,745.

Specification of Letters Patent.

Patented March 5, 1907.

Application filed September 8, 1904. Serial No. 223,780.

To all whom it may concern:

Be it known that I, HIRAM W. BLAISDELL, a citizen of the United States, residing at Los Angeles, in the county of Los Angeles and State of California, have invented certain new and useful Improvements in Transfer Mechanism; and I do hereby declare the following to be a full, clear, and exact description of the invention, such as will enable others skilled in the art to which it appertains to make and use the same.

This invention relates to machines or apparatus for effecting the transportation or transfer of mechanical appliances or machines in entirety, and particularly to the transfer of machines from one operative position to another; and some of the objects of the invention are to produce mechanical means of this general character which will be simple and cheap in construction and positive and efficient in operation.

Another object of the invention is to produce means for transporting or transferring machinery used to operate upon or cleanse covered filtration plants or systems, so that the field of usefulness of a treating or cleansing machine will be greatly enlarged and the cost of treating or cleaning a filtration plant correspondingly reduced.

Another object of the invention is to provide means for effecting the transportation of machines or apparatus from one place of operation of the latter to another place distant therefrom and to effect such transportation in a rapid and efficient manner with the minimum amount of manual labor.

It is also an object of this invention to provide a housing or protection for the treating or cleaning machinery when the latter is not in use.

Furthermore, an object of the invention is to effect the depression of a cleaning or treating machine into and the elevation thereof from a covered filtration plant or system and to effect the transfer of such machine from one operative position within such plant to another.

With these and other objects in view the invention consists, essentially, in the construction, combination, and arrangement of parts substantially as described more fully in the following specification and as illustrated in the accompanying drawings, forming part of this application, in which—

Figure 1 is an end elevational view of the machine or mechanism, showing portions of

the filter-covering in section and illustrating the transfer-table in operative position. Fig. 2 is side elevational view of the same. Fig. 3 is a top plan view of the transfer-table shown in Figs. 1 and 2. Fig. 4 is a detail side elevational view of the same, showing parts of a filter-cleaning or other machine in dotted lines. Fig. 5 is an end elevational view of the construction illustrated in Fig. 4. Fig. 6 is a top plan view of the gauntlet-crane, showing the propelling and operating mechanism. Fig. 7 illustrates the hanger-frame and transfer-table in inoperative position in the gauntlet-crane. Fig. 8 shows one construction of closed filter-bed with which the invention is designed to be used, and Fig. 9 is a detailed view of the hanger-frame.

Similar characters of reference designate corresponding parts throughout the several views.

This invention is particularly designed and constructed for use in connection with filtration plants or water-filtration works, and especially with that subdivision or class thereof generally known as "covered filters," which are generally employed to avoid the difficulties inherent to keeping the filters operating properly during cold weather, caused by the disturbance of the top surface of the sand during the removal of the ice, the freezing of the surface after scraping, and the necessity of cleaning certain portions of the filters more frequently than the remainder of the area, resulting in abnormally high rates of filtration on the parts so cleaned. Covered filters also prevent the growth of algae, which produces rapid surface clogging on the filters in summer weather, and sedimentation is facilitated by the absence of light and wind.

The shape of filter-beds is generally rectangular in plan, and they are usually arranged in a plurality of parallel rows, which are generally covered by grained arches springing from the tops of columns or piers, because of the ease with which they may be constructed of brick, masonry, or concrete. Covered filters have many columns, piers, buttresses, &c., which pass through the filtering materials and interrupt the surface of the filter, thereby rendering much more difficult the operation of cleaning, scraping, or treating the filtering material.

To effect the transportation of a filter-cleaning machine from one set or group of filter-beds to another, and to effect the trans-

fer of such machine from one row or series of filter-beds to another, and to accomplish the foregoing objects in a cheap, simple, and efficient manner are the principal points of 5 this invention. Therefore, referring to the drawings, and particularly to the construction illustrated in Figs. 1 and 2 thereof, the reference character 1 designates a portion of the groined or other cover or roof of a covered 10 slow sand filtration plant or works before mentioned, and the cover or roof 1 is preferably supported upon piers or columns 2, substantially as shown, while a manhole or trap-door 3 is desirably formed in the roof 1 at one 15 or more suitable places therein, through which the cleaning or other machinery may be introduced into and withdrawn from the filter. Tracks or ways 4 are preferably located upon the upper surface of the roof or 20 cover 1 on each side of the opening or trap-door 3 and are adapted to receive the supporting-wheels 5 of a gauntree-crane or traveling structure 6 of any preferred construction. Preferably upon the top of the gauntree- 25 crane is mounted a motor 7 or other actuating device, having a driving-pinion 8, meshing with a driven gear 9, having a double clutch-hub loose on an actuating-shaft 10, carrying beveled pinions 11, engaging similar pinions 12 on screw-actuating shafts 13, 30 each carrying beveled pinions 14, meshing with similar pinions 15, mounted upon the upper end of the vertical screws or threaded rods 34, preferably revolvably mounted in 35 each corner of the gauntree-crane, substantially as shown.

By means of the mechanism just described the depending or hanger frame, the transfer-table, and the filter-cleaning or 40 other machine may be raised within the gauntree-crane and transported therewith from one place of operation to another or lowered therefrom into operative position substantially as hereinafter described.

45 To effect the propulsion of the gauntree-frame, a gear-wheel 17 is loosely mounted upon the actuating-shaft 10, having a clutch-hub constructed to engage with the similar hub on the gear-wheel 9, so that when in such 50 engagement the wheel 17 is driven by the driving gear-wheel 9, which is thus out of driving engagement with the shaft 10, or the driving gear-wheel is thrown in one direction to operate the elevating and lowering 55 mechanism and in the other direction to operate the propelling mechanism. The gear-wheel 17 preferably meshes with a similar wheel 18 on a counter-shaft 19, carrying a bevel-pinion 20, meshing with a like pinion 60 21 on a short shaft 22, carrying a bevel-pinion 23, engaging a similar pinion 24 on a vertical shaft or propelling-rod 25, carrying a beveled pinion 26, meshing with a like pinion 27 on a propelling-shaft 28, having a pinion 65 29 engaging a gear-wheel 30 on a counter-

shaft 31, carrying a pinion 32, meshing with a gear-wheel 33 on the shaft of one of the supporting-wheels 4 of the crane.

Each of the screws 34 has threaded connection with a depending or hanger frame 35, of suitable construction, preferably provided with sections of tracks or short supporting-ways 36, desirably extending in approximately the same direction as the tracks 4 upon the cover of the filter, and the track-sections 36 are adapted when the hanger-frame 35 is lowered, as shown in Figs. 1 and 2, to register with and fill out or complete the tracks or supporting-ways 37, formed on or connected with each side of the upper portion of the piers or columns 2 and preferably extending longitudinally of the filter-bed and along one side thereof.

Referring to the construction illustrated in Fig. 2 of the drawings, it will be seen that the tracks 37 do not extend entirely across the filter-bed, but only as far as the opening or trap-door 3 in the roof or cover of the filter, substantially as shown in Figs. 1 and 2 of the drawing, in order that the lowering of the hanger-frame 35 into said opening will complete the tracks 37 by means of the track-sections 36, carried by said frame, as will be readily understood by those skilled in the art to which this invention appertains.

A transfer table or frame 38 is preferably mounted on supporting devices or wheels 39, Figs. 1 to 5, adapted to be supported by and travel on the track-sections 36, carried by the hanger-frame 35 and the tracks 37, supported from the columns or piers 2, whereby the transfer-table 38, with the cleaning or other machinery supported therefrom, as shown in dotted lines in Fig. 4, can be transferred from one gallery or row of arches to another to permit the use of such machinery in each gallery.

The transfer-table 38 is preferably propelled over the track-sections 36 and the tracks 37 by means of a motor 40, having a driving-pinion 41, meshing with a gear-wheel 42 on a worm-carrying shaft 43, the worm whereof engages a worm-wheel 44 on one of the propelling-shafts 45, rigidly connected with two of the supporting-wheels 39 of the transfer-table 38, substantially as shown in Figs. 3 to 5 of the drawings. The motor 40 preferably receives power or electricity from trolley or feed wires 46, Fig. 2, desirably extending along one side of the filter-bed, substantially in the same direction as the tracks 37, and the hanger-frame 35 preferably carries a section 47 of trolley or feed wire to complete the wire 46 when the hanger-frame is in operative position, substantially as shown, and trolleys 48 are preferably mounted on the transfer-table 38 to take the current from the wires 46 and 47 and deliver the same, through suitable electrical connections, to the motor 40.

The transfer-table 38 is preferably provided with a plurality of depending arms 49, constructed to support sections of track 50 or short supporting-ways adapted, when in registering position with the tracks or supporting-ways 51 on the piers 2, to complete the latter under the opening 3 in the filter roof or cover, as will be readily understood, and a section 57 of trolley or feed-wire may be carried by said transfer-table to complete the trolley-wire 53, from which the cleaning or other machinery may take power.

The operation of this invention will be readily understood from the foregoing description when taken in connection with the accompanying drawings and the following explanation thereof. When it is desired to clean or operate upon a closed filter, the gauntlet-tree-crane, with the hanger-frame 35, the transfer-table 38, and the cleaning machinery then elevated thereinto, is progressed along the tracks 4 upon the roof or cover of the filter until the crane and its contents are over the opening or trap-door 3 in said roof, such propulsion being effected through the motor 7, (supplied with power in any suitable manner,) pinion 8, gear-wheel 9, shaft 10, gear-wheels 17 and 18, counter-shaft 19, pinions 20 and 21, shaft 22, pinions 23 and 24, propelling-rod 25, pinions 26 and 27, propelling-shaft 28, and chain of gears to shafts of supporting-wheels 5, as before described. The gauntlet-tree-crane and contents being thus in position above the roof-opening, the propelling mechanism is stopped, and the elevating and depressing mechanism is started by throwing the clutch device out of engagement with the propelling mechanism and into engagement with raising and lowering mechanism, whereby the hanger-frame 35, transfer-table 38, and cleaning or other machine are lowered into operative position, substantially as shown in Figs. 1 and 2 of the drawing, whereupon the transfer-table 38 and machine supported therefrom can be moved upon the track-sections 36 on the hanger-frame 35 and on the rails 37 across the filter-bed, so that the machine can be stopped in any gallery or row of arches wherein it is desired to operate the machine, which will then be moved from the rail-sections 50 of the transfer-table onto the rails 51 upon the columns or piers 2, as will be readily understood.

Although this invention has been described and shown in connection with covered filtration plants, yet it is not intended to limit or confine the same to such use, as the invention was thus disclosed merely as an application thereof, for the invention is equally capable and applicable to many other uses or in various other connections. Furthermore, it is not desired to limit or confine this invention to the specific construction, combination, and arrangement of parts herein shown and

described, and the right is reserved to make all such changes in and modifications of the same as come within the spirit and scope of the invention.

I claim—

1. A transfer mechanism comprising a track, a vehicle adapted to run on said track, an incomplete track on a plane beneath said first-mentioned track and means carried by said vehicle to complete said incomplete track. 70

2. A transfer mechanism comprising a track, a vehicle adapted to run on said track, an incomplete track on a plane beneath said first-mentioned track and extending at an angle thereto and means carried by said vehicle to complete said incomplete track. 80

3. A transfer mechanism comprising a track, a vehicle adapted to run on said track, an incomplete track on a plane different from the plane of the first-mentioned track and means carried by said vehicle to complete said incomplete track. 85

4. A transfer mechanism comprising a track, a vehicle adapted to run on said track, an incomplete track on a plane different from the plane of the first-mentioned track and extending at an angle to said track and means carried by said vehicle to complete said incomplete track. 90

5. A transfer mechanism comprising a main support, an incomplete track beneath said support, a movable member supported from said main support and means carried by said movable member to complete said incomplete track. 95

6. A transfer mechanism comprising tracks, a main support, wheels on said support adapted to travel on said tracks, means for propelling said support, incomplete tracks or ways beneath said support, a movable member supported from said main support and tracks carried by said movable member adapted to complete said incomplete tracks. 105

7. A transfer mechanism comprising a traveling main support, incomplete tracks or ways beneath said support, a movable member carried by said main support, tracks carried by said movable member to complete the incomplete tracks, means for raising and lowering said movable member, a transfer member adapted to travel on said completed tracks and track-sections on said transfer member adapted to complete other tracks, the parts being so arranged that apparatus carried by said transfer member may be operated in different directions. 115

8. A transfer mechanism adapted for use with a covered chamber comprising a main support adapted to travel over the cover of said chamber, a movable member carried by said support and adapted to be lowered through an opening in said cover into said chamber and to be raised therefrom, incomplete tracks within said chamber and track- 120 125 130

sections carried by said movable member adapted to complete said incomplete tracks.

9. A transfer mechanism adapted for use with a covered chamber comprising a main support adapted to travel over the cover of said chamber, a movable member carried by said main support and adapted to be lowered through an opening in said cover into said chamber and to be raised therefrom, incomplete tracks within said chamber, track-sections carried by said movable member adapted to complete said incomplete tracks and a transfer member adapted to travel on the tracks so completed.
10. A transfer mechanism adapted for use with a covered chamber comprising a main support adapted to travel over the cover of said chamber, a movable member carried by said main support and adapted to be lowered through an opening in said cover into said chamber and to be raised therefrom, incomplete tracks within said chamber, track-sections carried by said movable member adapted to complete said incomplete tracks,
- 20 a transfer member adapted to travel on the tracks so completed, other incomplete tracks within said chamber and track-sections carried by said transfer member adapted to complete said last-named incomplete tracks, the
- 25 parts being so arranged that apparatus supported by said transfer member can operate within said chamber in different directions.

11. The combination with a covered chamber, an opening through said cover into said chamber, tracks upon said cover and a plurality of incomplete tracks within said chamber extending at an angle to each other, of a transfer mechanism comprising a main support adapted to travel on the first-mentioned tracks, means for effecting said travel of said main support, a movable member, means for effecting the elevation and depression thereof, track-sections carried by said movable member adapted to complete one set of said incomplete tracks, a transfer member adapted to travel on the tracks so completed and track-sections on said transfer member adapted to complete the other set of said incomplete tracks, the parts being so arranged that apparatus supported by said transfer member may travel on the tracks thus completed.

12. The combination of a covered filter, an opening through said cover into said filter and tracks upon said cover, of a main support constructed to travel on said tracks, means for effecting said travel of said main support, a movable member, screws supporting said movable member in said main support adapted to raise said member into said support and to lower the same through said opening into said filter, means for operating said screws, tracks within said filter running longitudinally thereof and extending to the edges of the opening through the filter-cover,

track-sections carried by said movable member adapted to complete the longitudinal tracks across said opening, a transfer member adapted to travel on said tracks so completed, tracks within said filter running transversely thereof and extending to the edges of said opening through the filter-cover and track-sections carried by said transfer member adapted to complete said transverse tracks the parts being so arranged that apparatus supported by said transfer member is capable of transverse and longitudinal movement within said filter.

13. The combination with a covered chamber having an opening through the cover thereof and tracks within said chamber beneath said cover, of a transfer mechanism adapted to carry an apparatus to said opening, means for lowering said apparatus into said chamber and means for effecting the movement of said apparatus within said chamber on said tracks.

14. A transfer mechanism for covered filters comprising a main support, a movable member adapted to be lowered and raised through an opening in the cover of said filter and a transfer member adapted to support an apparatus for operating upon the filter-bed.

15. A transfer mechanism for covered filters comprising a main support, a movable member, means for lowering and raising the latter through an opening in the filter-cover, incomplete tracks beneath the filter-cover, track-sections carried by said movable member adapted to complete said incomplete tracks, other tracks beneath said filter-cover and a transfer member adapted to travel on one of the sets of tracks beneath said cover.

16. The combination of a covered filter, exterior tracks on said cover, incomplete longitudinal and transverse tracks within said cover, a crane adapted to travel on said exterior tracks, a hanger-frame movably mounted in said crane, means for lowering said hanger-frame through an opening in the filter-cover and for raising the same within said crane, track-sections on said frame adapted to complete the incomplete longitudinal tracks, a transfer-table adapted to travel on said completed tracks and track-sections carried by said transfer-table adapted to complete said incomplete transverse tracks and to support an apparatus to operate upon the filter-bed.

17. The combination with a covered filter, of exterior tracks on the cover of said filter and a transfer mechanism comprising a main support adapted to travel on said exterior tracks, means for effecting said travel, a movable member, means connecting said movable member and said support whereby said movable member may be lowered through an opening in the filter-cover and raised within said main support, incomplete

longitudinal and transverse tracks beneath said cover, track-sections carried by said movable member adapted to complete said longitudinal tracks, a transfer member adapted to travel on the track so completed and track-sections carried by said transfer member adapted to complete said transverse tracks, the parts being so arranged that apparatus supported by said transfer member is capable of either longitudinal or transverse movement on the tracks within said filter.

18. A transfer mechanism adapted for use with a plurality of covered filter-beds, tracks 15 on the covers of said filter-beds, means adapted to travel from one filter-bed to another on said tracks and adapted to be lowered through an opening in the covers of said filters and to be raised therefrom and apparatus arranged to operate within said filters 20 and carried by said last-mentioned means.

19. In a covered filter the combination of a crane adapted to be moved over the cover, a hanger-frame supported from said crane 25 and adapted to be raised and lowered thereby, a transfer-table carried by said hanger-frame and tracks beneath the cover adapted to receive the transfer-table.

20. The combination with a covered filter having an opening thereinto, of a track adjacent to said opening, a vehicle adapted to run on said track, an incomplete track on a plane different from the plane of the first-mentioned track and means carried by said vehicle to complete said incomplete track. 30 35

21. The combination with a covered filter comprising a plurality of bays extending at an angle to each other and having an opening into one of said bays, of a track adjacent to said opening and extending down one of said 40 bays, a vehicle adapted to run on said track, incomplete tracks on a plane different from the plane of the first-mentioned track and extending down the bays running at an angle to the last-mentioned bay and means carried 45 by said vehicle to complete said incomplete tracks.

In testimony whereof I have signed my name to this specification, in the presence of two subscribing witnesses, at Los Angeles, 50 county of Los Angeles, State of California, this 27th day of August, 1904.

HIRAM W. BLAISDELL.
